UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed November 30, 1927. Serial No. 236,722.

The present invention relates to improvements in refrigerating apparatus and more particularly the cold producing or refrigerating elements used in mechanical refrigerators.

It is an object of the invention to provide an improved refrigerating element particularly adapted for use in large commercial refrigerators. The invention contemplates the provision of a refrigerating element which will efficiently cool relatively large commercial cabinets and whose parts are so constructed and arranged as to permit easy handling without engendering undue stresses and strains on the joints of the element.

The invention also contemplates so constructing the refrigerating element that the frost which may build thereupon and thus exert weight upon various parts thereof will not injure the joints of the elements.

Further objects and advantages of the present invention will be apparent from the following description, reference being had to the accompanying drawings wherein a preferred embodiment of the present invention is clearly shown.

In the drawings:

Fig. 1 represents a top view of the improved refrigerating element of the invention;

Fig. 2 shows a side view of the same;

Fig. 3 is an end view of the refrigerating element; and

Fig. 4 illustrates a large commercial refrigerator cabinet equipped with the improved refrigerating element of the invention; said cabinet being provided with means for producing an efficient circulation of chilled air.

Referring in detail to the drawings, it will be observed that the improved refrigerating element comprises a header 10 which serves as a container for a refrigerating medium which may, for example, be liquid sulphur dioxide. This header serves to distribute the refrigerant to ducts or pipes hereinafter described in detail. The refrigerating medium is led into the header by means of a pipe 11 and is led off therefrom above the liquid

suitable float valve, such as that diagrammatically shown in Fig. 2 as 23 is used to control the flow of refrigerant to the header and is adapted to maintain a constant level of liquid in the tank.

A series of cooling coils or refrigerant circulatory pipes which are formed of a plurality of dependent ducts or loops of pipes are connected to the header in parallel circuit relation as shown in the drawings in Figs. 2 and 3, the joints being soldered to insure a tight connection. These ducts extend downwardly into the air cooled by the refrigerating element. The loops or ducts constituting the system of circulating ducts are constructed substantially as follows: Each loop has a vertical leg 13, (Fig. 2) depending vertically downwardly and offset laterally a substantial distance from the header 10 as well as another leg 13' which extends in a similar manner but on the opposite side of the header. These loops are joined by horizontal pipes or ducts arranged in two systems or sets, the bottom set consisting of ducts 14 to 20 inclusive being relatively long and adapted to connect the vertically depending legs or ducts 13 and 13' while the other, upper set, likewise horizontal, is composed of shorter members 14' to 20' which connect the vertically depending ducts 13 and 13' with the header. In Figs. 2 and 3 it will be observed that the duct loops comprising the vertically depending legs 13 and 13' and the joining members or connecting pipes are composed of individual duct loops each of which may individually be considered as a loop system of its own, dependent in a plane which is substantially parallel to the vertical axis of the plane of the header. All but the two exterior or most laterally disposed loops are of the same size, but bent away from their neighboring loops. In this manner only two sizes of loops are necessary. These loops are preferably so arranged that the refrigerating element constitutes a symmetrical unit by having half of the vertically disposed loops on one side of the header arranged exactly like the vertically disposed loops on the other side of the header, a central duct loop 17 being considered a dividing plane. The duct

loop systems are connected with the header by means of short pipes 24 which radiate outwardly from the header as shown in Fig. 3, thus causing the header to surmount the duct loops.

Each duct loop is preferably provided with a fin 21 composed of a good heat conducting material such as copper, the said duct loops being attached thereto in good thermal relation as by soldering or the like. These fins increase the effective cooling surface of the ducts. The symmetrical arrangement above mentioned may be preserved by attaching the fins to one side of the coils located on one side of the header and to the other side of the coils located on the other side of the header, as shown in Fig. 3.

Tie rods or braces 22 are attached at intervals on the fins to prevent distortion during handling.

It is apparent that the structure above described furnishes a refrigerating element which is capable of being built in large sizes, for example comparable to that of a cake of ice, and that the fins produce large heat absorbing surfaces and passage-ways which aid in circulating and guiding the air cooled by the refrigerating ducts.

Fig. 4 shows the improved refrigerating element mounted in a large commercial refrigerator cabinet. The refrigerator comprises a cabinet having an exterior wall 30 and impervious interior lining 31, the space 32 in the walls being filled with corkboard or similar heat insulating material. A door 33 is provided which may be constructed solid like the walls, or if desired provided with a glazed portion the glass panels 34 of which serve to afford a view of the inside.

The improved refrigerating element above described is mounted in a chilling chamber 35 within the refrigerator cabinet, this chilling chamber comprising a heat insulated wall 36 so arranged as to form upper and lower flues 37 for the circulation of air. The refrigerating element is supported by a hanger system composed of braces 38 and hanger bars 39, the latter being preferably attached to the inside top of the cabinet. It is one of the features of the invention to support the refrigerating element in the cabinet by means of its fins. For this purpose the straps 38 pass completely around the finned body of the element and thus obviate stresses as well as simplify the installation and removal of the element. In this manner stresses are avoided and damage to the soldered joints, e. g. at the points where the loops enter the header is avoided. Such stresses are ordinarily caused by handling during installation, and during use by the frost which forms on the element, the frost acting by its weight to produce strains on the joints of the apparatus.

A drip board 40 of any suitable type is preferably disposed beneath the refrigerating element and connected with a drain 41 for removing drippage water when the refrigerating element is being defrosted. This drip board may, if desired, also serve as part of the structure of the chilling chamber 35, suitable provision being made for insuring a correct circulation of chilled air as by spacing the pan from the wall. Hooks 42 and other means such as shelf 43 for supporting meat, etc., form part of the usual structure of the cabinet.

In the operation of the refrigerator, cold air coming from the chilling compartment passes downwardly through the lower flue 37 after being partly deflected by the baffle 40 serving as the drip board. The cold air is directed over any meat hanging on the hooks 42 or located otherwise in the body 44 of the refrigerator. The air heated by contact with food in the refrigerator ascends and re-enters the chilling chamber through the upper flue 37 to be there cooled and recirculated as before.

It is apparent that the refrigerating element may be used in lieu of ice cakes and that the spread of the fins makes the element applicable for producing efficient cooling since the cooling effect of ice is merely that produced by the lapping of air over the surfaces of the ice cake. It is obvious that the finned loops present parallel passage-ways which in addition to having a far greater total area than is presented by the surface of a block of ice, promote also a very efficient circulation of air.

While the form of embodiment of the invention as herein disclosed, constitutes a preferred form, it is to be understood that other forms might be adopted, all coming within the scope of the claims which follow.

What is claimed is as follows:

1. Refrigerating means for mechanically refrigerated cabinets comprising an elongated header adapted to contain a quantity of liquid refrigerant, and ducts depending from said header for receiving liquid refrigerant therefrom and extending longitudinally beyond opposite ends of said header.

2. A cooling element for mechanical refrigerators comprising an elongated header adapted to contain a quantity of liquid refrigerant, and a series of ducts depending from the header for circulating liquid refrigerant, said ducts projecting longitudinally beyond the opposite ends of said header.

3. Refrigerating means for mechanically refrigerated cabinets comprising an elongated header, and a plurality of duct loops connected with said header and extending longitudinally beyond opposite ends of said header.

4. Refrigerating means for mechanically refrigerated cabinets comprising an elongated header and a plurality of duct loops connected with said header and extending longitudinally beyond opposite ends of said header.

gated header adapted to contain a quantity of liquid refrigerant ducts depending from said header and extending longitudinally beyond opposite ends of said header; said ducts being provided with fins attached in good thermal contact to said ducts.

tending longitudinally beyond the other end of said header, said duct means having portions extending laterally beyond the header.

In testimony whereof I hereto affix my signature.

JESSE G. KING. ⁷⁰

5. Refrigerating means for mechanically refrigerated cabinets comprising an elongated header, and a plurality of duct loops connected with said header and extending longitudinally beyond opposite ends of said header, said duct loops being provided with fins attached in good thermal contact to said ducts.

15 6. A refrigerating element for mechanical refrigerators comprising an elongated header, a series of duct means depending from said header and connected thereto in parallel circuit relation, certain of said duct means having one vertically depending leg located laterally offset to one end of said header and another vertically depending leg located laterally offset to the other end of said header.

7. A refrigerating element for mechanical refrigerators comprising an elongated header, a series of duct means depending from said header and connected thereto in parallel circuit relation, certain of said duct means having one vertically depending leg located laterally offset to one end of said header and another vertically depending leg located laterally offset to the other end of said header, said vertically depending legs being joined at their bottom by a relatively long horizontal duct extending in the same longitudinal direction as the body of said header and said vertically depending ducts being connected to said header by short horizontal ducts substantially parallel to said long horizontal duct.

40 8. A refrigerating element for mechanical refrigerators comprising an elongated header, a series of duct loops depending from said header and connected thereto in parallel circuit relation, said loops extending parallel to the body of said header and having one vertically depending leg located laterally offset to one end of said header and another vertically depending leg located laterally offset to the other end of said header, said vertically depending legs being joined at their bottom by a relatively long horizontal duct extending in the same longitudinal direction as the body of said header and said vertically depending ducts being connected to said header by short horizontal ducts substantially parallel to said long horizontal duct, each duct loop being offset laterally from its neighboring parallel duct loop.

60 9. A refrigerating element for mechanical refrigerators comprising an elongated header, a series of duct means depending from said header, certain of said duct means extending longitudinally beyond one end of the header and certain of said duct means ex-
